UNITED STATES PATENT OFFICE.

HERMANN WARK, OF NEW YORK, N. Y.

NAME OR SIGN PLATE.

SPECIFICATION forming part of Letters Patent No. 391,727, dated October 23, 1888.

Application filed April 11, 1888. Serial No. 270,265. (No model.)

To all whom it may concern:

Be it known that I, HERMANN WARK, of the city, county, and State of New York, have invented certain new and useful Improvements 5 in Name or Sign Plates, of which the following is a specification.

This invention has reference to an improved name or sign plate to be used for the letter-boxes of flat and tenement houses, and for 10 doors and signs generally; and the invention consists of a name or sign plate composed of an exterior frame provided with parallel longitudinal slits, a depressed panel-plate between the slits, re-enforced by a longitudinal 15 rib at the back and provided with notches at the rear side for attaching the bent prongs of the letters, which letters are placed in position along the face of the panel-plate, the prongs being passed through the slits and 20 bent into the notches at the rear side of the panel-plate.

In the accompanying drawings, Figure 1 represents a front elevation of my improved name or sign plate. Fig. 2 is a rear elevation of the same; Fig. 3, a vertical transverse section on line *x x*; Fig. 1 and Fig. 4 a side view of the letters used in connection with my improved name or sign plate.

Similar letters of reference indicate corresponding parts.

Referring to the drawings, A represents the main frame of my improved name or sign plate, which frame is provided with a raised or offset middle portion when the same is to be inserted into the fronts of letter boxes of 35 flat and tenement houses. When it is to be used for door-plates or signs, the offset for the raised middle portion is not required. The frame A is provided with two parallel longitudinal slits, *a a*, and a panel-plate, C, between the same, which is slightly depressed, so as to provide for the thickness of the letters B, which form the same, said letters being made 40 of cast metal or cut by means of dies from suitable sheet metal and provided with bent prongs *b*, as shown clearly in Figs. 2 and 4. The depressed panel-plate C is re-enforced by a longitudinal bar or rib, D, which is soldered to the rear side of the panel-plate and set by 45 its beveled ends into corresponding grooves of the frame A, as shown in Fig. 2. The panel-plate C is provided at each side of its rear edge with notches *d*, which serve to receive the bent prongs *b* of the letters B, so as

to keep the letters N in position at the front 55 part of the panel-plate C.

In making my improved name or sign plate a number of letters, B, are manufactured and their prongs *b* bent at right angles to the body of the letters. The letters forming any 60 required name are then placed in position on the panel-plate C, so that the prongs pass through the slits *a a* to the rear of the panel-plate, where they are bent over and into the notches after the proper spacing between the 65 letters has been arranged. The prongs hold the letters rigidly in position, so as to prevent the shifting of the same along the front of the panel-plate C. The main frame may be made of cast metal, hard rubber, or other suitable 70 material, the panel-plate being preferably provided with a grain, so as to form a background for the letters, while the surrounding surface of the surrounding frame is preferably polished. In this manner a name or sign plate 75 can be made up within short notice, with any desired name and in a very neat and finished manner, and thereby the unsightly written or printed cards which are at present in use for indicating the names on letter-boxes 80 and doors be dispensed with and a comparatively cheap and neat plate furnished in their place.

Having thus described my invention, I claim as new and desire to secure by Letters Patent— 85

1. A name or sign plate consisting of a main frame having parallel longitudinal slits, a panel-plate between said slits made integral with the main frame and provided with notches at its rear edges, and letters having 90 bent prongs which are inserted into the slits and applied to said notches, substantially as set forth.

2. A name or sign plate composed of a main frame having parallel longitudinal slits, 95 a depressed panel-plate between said slits, a longitudinal re-enforcing bar or rib extending along the rear of the panel-plate, notches at the rear edges of the panel-plate, and letters provided with prongs that pass through the 100 slits and engage the notches, substantially as set forth.

In testimony that I claim the foregoing as my invention I have signed my name in presence of two subscribing witnesses.

Witnesses: HERMANN WARK.

PAUL GOEPEL,

JOHN C. EBMEYER.
